ABSTRACT OF THE DISCLOSURE

Apparatus and method for providing a liquid storage tank with a gas blanket comprising a storage tank for storing therein a liquid and a pressurized gas supply means for supplying gas under pressure to the tank. A supply line is coupled to both the tank and the gas supply means. Pressure control valve means is coupled to the supply line and regulated by the pressure within the storage tank. A return line is coupled to both the supply line and the gas supply means. Compressor means is disposed in the return line for compressing the gas therein and second-mentioned pressure control valve means is coupled to both the compressor means and the return line wherein the pressure in the supply line regulates the pressure of both pressure control valve means.

BACKGROUND OF THE INVENTION**Field of the invention**

The present invention relates to a method and apparatus for providing storage tanks for liquids, particularly for substances in the hot-liquid state such as bitumen, with a gas blanket. Unlike conventional blanketing gas plants, the apparatus is also suitable for blanketing storage tanks arranged singly or in small groups.

Description of the prior art

Storage tanks are normally blanketed with a blanketing gas, usually with a gas which is poor in oxygen, by supplying a gas stream at slightly excess pressure and allowing the excess gas to escape by means of a pressure-maintenance valve. The quantity of the gas supplied must be sufficient to equalize any sudden variations in pressure and volume within the gas cap in the storage tank, for example when the tank is being emptied. As a blanketing gas, use is normally made of exhaust gas passed from a suitable furnace through the necessary coolers and condensation traps. These blanketing gas plants are large and expensive to operate and maintain; they are therefore only suitable for relatively large tank installations, for example, in oil refineries. They can be simplified by using steel bottles containing highly compressed nitrogen instead of the complicated combustion and cooling installations. However, the continuous consumption of pressure gas makes plants of this type too expensive for most purposes.

In contrast, for the storage of at least partially highly volatile liquids such as liquefied hydrocarbon gases or crude oil, use is made of apparatuses which prevent gases from escaping from the storage tanks. It is known, for instance, to group storage tanks for liquefied gas, with the use of compressors, in such a way (U.S. patent specification 2,885,109) that the lack or excess of gas from tanks which are being emptied or filled is equalized over these tanks or over tanks which are not being emptied or filled. It is also known to discharge the excess gas from crude oil tanks through an exhauster into a gathering

2

pipeline, and to make up any deficiency of gas from the same gathering pipeline by means of a bypass line for the exhauster (U.S. patent specification 2,899,013). Thus these measures, too, maintain a protective blanket in the storage tank. However, a condition of their use is the presence of highly volatile liquids, and they are also by nature only applicable in large tank installations.

It has now been found that certain difficult or non-volatile mineral oil products, in particular many high-melting bitumens in the hot-liquid state, should be stored under a gas blanket to prevent quality deterioration. In the processing plants, whose farms usually contain only a few tanks, these products have to be maintained at temperatures in excess of 200° C. The conventional blanketing gas plants, however, are not suitable on account of their size, quite apart from the fact that continuous venting of blanketing gas loaded with bitumen vapors would create a very unpleasant smell in the installation and surroundings.

SUMMARY OF THE INVENTION

The apparatus and method according to the invention for providing storage tanks with a gas blanket is characterized by a pressure-gas container for the blanketing gas supply, a supply line with a control valve regulated by the pressure in the storage tank, and a return line with a compressor arranged parallel to the control valve and also regulated by the pressure in the storage tank.

The storage tank preferably is sealed off as completely as possible from the ambient atmosphere and is preferably provided with a safety valve against excess pressure and sub-atmospheric pressure in order to prevent damage in the event of unexpected failures. The conventional dip-hatch is better avoided, since it allows blanketing gas to escape, at least during gauging. The storage tank is preferably suitably fitted with a closed level gauge (known per se), for example a float device with magnetic indication transfer.

With this apparatus, the supply of blanketing gas shuttles, depending on the operating conditions, between the pressure-gas container and the virtually pressure-free storage tank, and unpleasant vapors are thus prevented from escaping into the atmosphere.

BRIEF DESCRIPTION OF THE DRAWING

The drawing is a schematic illustration of a preferred embodiment for carrying out the teachings of this invention.

**DESCRIPTION OF THE PREFERRED
EMBODIMENT**

Referring to the drawing, a pressure tank 1, which contains a supply of blanketing gas, is connected by way of supply line portion 9 to a pressure control valve 2. Supply line portion 10 leads from valve 2 to a main supply line 3 leading to a storage tank 4. Control valve 2 is regulated by conventional pressure control means 11, coupled to both valve 2 and supply line 3. Supply line 3 also leads to a return line 21 having a control valve 12 and a compressor 5 which is controlled by a conventional compressor control means 13 coupled to pressure control means 14. Control means 14 is also coupled to supply line 21 which is in turn coupled to supply line 3 so that the pressure in supply line 3 regulates both the pressure of control means 11 and 14 and thus control valve 2 and compressor 5. Return line 21 then passes from compressor 5 through a nonreturn check valve 6 and into pressure tank 1. Supply line 3 is connected to storage tank 4 without shut-off or throttling means and its length and cross-sectional diameter is so dimensioned that it maintains the same pressure over substantially its entire length as the pressure in storage tank 4. A conventional devaporizing or

ondensing means 7, such as a liquid separator or cooler, disposed between supply line 3 and storage tank 4 for condensing any gases exiting from tank 4 before any quids from the gases enter line 3. Vacuum safety valves and 15 may be provided at storage tank 4 and pressure tanks 1, respectively. The pressure in pressure tank 1 may be controlled by pressure control valve 16. A pressurized as supply means 17, controlled by control valve 18, is 5 referably coupled to supply line 3. Liquids into and out of storage tank 4 may be selectively introduced and 10 withdrawn by means of control valves 19 and 20, respectively, as illustrated in the drawing.

Since, as a rule, the storage tanks in question will stand p better to a slight excess pressure than to sub-atmospheric pressure, the control is suitably set in such a way 15 that the control valve 2 responds at the latest when the ambient pressure has been reached, while the compressor is switched on at an excess pressure of, for example, a 5 mm. water column. The control range must, of course, 20 be contained within the response limits of the excess pressure and vacuum safety valve 8; in a suitable embodiment, only approximately the middle third of the safety range is utilized. To begin operations, the entire system is filled up with nitrogen from a suitable gas supply means 25 7, such as steel bottles, until a pressure of several g./cm.² is reached in the pressure tank 1. At a later stage the leakage losses only have to be made up from time to time, when the pressure in this tank has dropped 30 to such a level that when the storage tank 4 is being emptied rapidly the provision of a gas blanket by way of the control valve 2 is no longer guaranteed.

EXAMPLE

By way of example, it was found that a 45 m.³ storage tank in which a special bitumen is stored at 200° C.-230° 35 L. and which is filled, when necessary, at a pumping speed of approximately 12 m.³/h., can be maintained reliably under blanketing gas (nitrogen) under all operating conditions by means of the following equipment: a pressure tank 1 with a capacity of 5 m.³ and the operating pressure of 8 kg./cm.²; an electromagnetic control valve ID-10 2, controlled by a pressure switch at 0.10 mm. water column; a shuttle line NW-25 3; a signal-stage reciprocating compressor 5, with a delivery of 16 m.³/h. at a compression pressure of 8 kg./cm.², controlled by a 45 pressure switch at 55-63 mm. water column; and an air cooler 7 from ribbed cooling pipes NW-25 with a total length of approximately 8 mm.

In addition to the foregoing, the apparatus and method of this invention appreciably reduces the formation of coke deposits in bitumen storage tanks; consequently the frequency of cutting the tanks down for cleaning is decreased. Thus, the apparatus of this invention is particularly applicable to the gas blanketing of hard grades of bitumen with high storage and processing temperature such as 200-260° C.).

We claim as our invention:

1. Apparatus for providing a liquid storage tank with a gas blanket comprising:
a storage tank adapted to contain therein a liquid;
pressurized blanketing gas supply means for supplying a blanketing gas under pressure to said tank;
a supply line coupled to both said tank and said blanketing gas supply means;
pressurized make-up gas supply means coupled to said supply line for selectively admitting gas under pressure thereto;
a valve in said supply line;
first pressure control means operatively coupled to said supply line and regulated by the pressure within said storage tank to control said valve;
a return line coupled to both the supply line and said blanketing gas supply means;
compressor means disposed in said return line for compressing said gas therein; and
second pressure control means operatively coupled to both said compressor means and said return line whereby the pressure in said supply line regulates the pressure of both said first and second pressure control means.
2. The apparatus of claim 1 including de-vaporizing means disposed in said supply line for condensing any gases leaving said storage tank.
3. The apparatus of claim 2 whereby said storage tank is substantially sealed off from the ambient atmosphere; and
safety valve means associated with said storage tank for selectively protecting said tank from both excess and sub-atmospheric pressures.
4. The apparatus of claim 1 wherein the supply line has a length and cross-sectional diameter such that said supply line maintains the same pressure over substantially its entire length as the pressure within said storage tank.
5. The apparatus of claim 1 whereby said storage tank is substantially sealed off from the ambient atmosphere; and
safety valve means associated with said storage tank for selectively protecting said tank from both excess and sub-atmospheric pressures.
